UNITED STATES PATENT OFFICE.

LAWRENCE MAPLES, OF CHICAGO, ILLINOIS.

WASHING-MACHINE.

1,350,823.

Specification of Letters Patent. Patented Aug. 24, 1920.

Application filed April 12, 1920. Serial No. 373,077.

To all whom it may concern:

Be it known that I, LAWRENCE MAPLES, a subject of the King of Great Britain, and a resident of Chicago, in the county of Cook 5 and State of Illinois, have invented certain new and useful Improvements in Washing-Machines; and I do hereby declare that the following is a full, clear, and exact description thereof, reference being had to the accompanying drawings, and to the characters of reference marked thereon, which form a part of this specification.

This invention relates to a novel support for an agitating device, such for instance 15 as the dolly of a washing machine, wherein the mechanism for operating the agitating device is sustained on the support, which latter is in turn sustained on the rim of a vessel such as a tub, barrel or the like for 20 containing the material to be agitated.

The present invention is shown as adapted to a washing machine and in such adaptation the agitating device is a known form of dolly whose operating shaft extends upwardly through the support and is connected by gearing to the actuating mechanism, which latter may be a hand driven or a power driven device. For the practical purposes of a device of this character the mechanism will usually be operated by hand 25 power.

The principal purpose of the invention is to provide a very simple, economical and rugged support for an agitating mechanism 35 which, by its addition and the addition of the actuating parts for the agitating mechanism, enables an ordinary open top vessel, as a tub, barrel, to be converted into a washing or like machine so that thereby, having 40 a substantial, rugged vessel of this character at hand, it becomes practicable to produce a washing machine having all of the functions of a more expensive machine, at a very economical cost.

Another purpose of the invention is to produce a support for a washing machine mechanism of this character which is constructed to be adapted to vessels of different diameters, there being adjusting means 50 for adjusting the support to the vessel to hold it firmly thereon while adapting the support or attachment to vessels of different diameters.

Other objects of the invention are to improve and simplify devices of this general character, and the invention consists in the

combination and arrangement of the parts shown in the drawings and described in the specification, and is pointed out in the appended claims.

60

In said drawings—

Figure 1 is a perspective view, looking from the upper side, of an agitating device and a support therefor embodying my invention, showing in dotted outline a vessel, 65 as a tub, on the rim of which the support is sustained;

Fig. 2 is a perspective view of the support and mechanism as seen from beneath; 70

Fig. 3 is an enlarged section on the line 3—3 of Fig. 1.

As shown in the drawings, 10 designates a vessel which may be of any known character. It is herein shown as having the 75 form of a tub, and may be a sheet metal or galvanized iron tub with the usual bead rim 11.

The support, designated as a whole by 12, has the form of a spider comprising 80 four arms 14 radiating from a center, which center is the axis of the shaft 15 of the dolly 16 or other agitating element. These arms of the spider may conveniently be the four end parts of two intersecting members 85 which may be joined at their crossing point in any suitable manner. As herein shown, said arms 14 are made of relatively heavy gage sheet metal,—galvanized metal being suitable, and they are fixed together at their 90 intersection by means of a relatively heavy wood disk or block 17 that acts as a rigidifying element for the spider and supports the operating mechanism hereinafter to be described. The means for attaching the 95 said disk or block 17 to the arms 14 comprises bolts or rivets 18 that extend through the block or disk 17 and through the underlying metal bars that constitute the arm 14,—some of these rivets or bolts 18 constituting the means for attaching the agitator actuating mechanism to the block or disk 17, as will hereinafter be described.

The outer ends or terminals of the arms 14 take the form of downturned flanges or 105 hooks 19 that engage over the rim of the vessel 10 and are preferably curved to correspond to the curvature of the rim. The said hook-shaped terminals of the spider arms may be fixedly attached to the vessel 10 by means of thumb screws 20, which are threaded through the hooks 19 and are

100

110

adapted to bear at their ends against the outer side of the vessel 10.

If the device is intended to be made for a vessel of a single given diameter the said spider arms may be made non-extensible or continuously integral. However, it is desirable, in order to lessen the number of standard supports or equipments required to be kept in stock, to provide means whereby the support is adjustable to the vessels. A practical way of thus adjusting the spider arms to vessels or receptacles of different diameters is to make each arm of two parts 21 and 22 with their ends adapted to lie one over the other in a generally overlapping or telescopic arrangement and to provide one of the members of the overlapping parts of each arm, the lower member 21 as shown, with a slot 23 through which extends a headed pin or screw 24, the head of which bears against the lower member at the sides of the slot 23, and the upper end of which pin or screw is threaded to extend through a registering opening in the upper member 22 to receive a thumb nut 25. Thus each arm may be elongated, and through the screw pins 24, the parts thereof are locked rigidly together. As a further means for producing a rugged adjusting connection between the two members 21 and 22 of each arm, one of the members, the lower member 21 of each arm, is made wider than the other member and is turned upwardly at its side margins, beyond the intersection of the spider arms, to produce guide flanges 26 within which to receive the other or upper member of the adjustable arm, as best shown in Figs. 1 and 3.

In order to carry out the principle of the telescopic spider arms for adjustably adapting the support to vessels of different diameters, the lower members 21 of the spider arms, and which are the fixed members, extend continuously across the intersecting point of the spider arms and are fashioned at the upper sides of their ends to produce the guide flanges 26, and the hooked members 22 are relatively short pieces that are overlapped on the ends of the parts 21 within said hooked flanges a sufficient distance to give the desired range of adjustment. At the centers of the members 21 or where they intersect and are connected together, the full widths of the members are maintained, as shown at 27, so as to give reliable joining effect or connection at the intersections of the spider arms, as best shown in Fig. 2.

The mechanism for actuating the agitating element 16 is a simple mechanism. It comprises as herein shown a horizontal bevel pinion 28 which is fixed to the shaft 15 of the agitating device or dolly and a large bevel gear 29 that is mounted to rock on a stud 30 which is fixed to and extends laterally from a suitably shaped standard 31 that is integral with and rises from the base cast-

ing 32 of a bracket that is supported on the disk or block 17. The said gear wheel is provided with a socket 33 to receive an operating handle 34. The said casting or bracket for supporting the operating mechanism has a bearing 36 to receive the extreme upper end of the agitator or dolly shaft 15.

The construction described is a very simple one which can be made at small cost and readily assembled, inasmuch as it is practicable to make the spider parts of sheet metal of the required gage; and said spider members can be fastened to each other and to the block by simple fastening expedients,—the bolts or rivets 18, some of which latter, as before stated, constitute means for fixing the operating mechanism bracket to the support. Another advantage of the construction described, in addition to its adjustability to different sized vessels 10 is that the members of the spider arms are made of sufficient width to afford sufficiently wide bearings between them to prevent the spider arms or members twisting under operating stresses; and this in addition to the sliding flanged connection of one of the members of each spider arm with the other member produces a very rugged structure and one which will withstand hard usage without danger of the parts getting out of alignment.

If desired, the angular spaces between the spider arms may be filled by sheet metal segments so as to entirely cover the top of the tub, with one of said segments hinged to constitute a door; but in practice this expedient in many uses of the device will not be necessary.

I claim as my invention:

1. An improved support for an agitating device to convert a tub or like vessel into a washing machine, comprising a frame having intersecting flexible arms adapted to engage over the rim of the vessel and to be confined thereon, and an axially disposed rigidifying element fitted over the intersection of said arms and attached to said arms for supporting an agitator shaft and the mechanism for actuating it.

2. An improved support for an agitating device to convert a tub or like vessel into a washing machine, comprising a frame having intersecting flexible arms adapted to engage over the rim of the vessel and to be confined thereon, and an axially disposed rigidifying element fitted over the intersection of said arms and attached to said arms for supporting an agitator shaft and the mechanism for actuating it, and means for locking the free ends of said arms over the rim of the tub, and tensioning said flexible arms.

3. An improved support for an agitating device to convert a tub or like vessel into a washing machine, comprising a frame having intersecting flexible arms adapted to

engage over the rim of the vessel and to be confined thereon, and an axially disposed rigidifying element fitted over the intersection of said arms and attached to said arms 5 beyond the intersecting portions thereof, and provided with an opening in register with an opening in the frame to receive a bearing for an agitator shaft.

4. An improved support for an agitating 10 device to convert a tub or like vessel into a washing machine, comprising a frame having radiating flexible arms adapted to engage over the rim of the vessel and to be confined thereon, and an axially disposed rigidifying element at the intersection of said 15 arms for supporting an agitator shaft and the mechanism for actuating it, said arms being telescopic, and provided with locking means coöperating with the telescopic means to securely lock the arms on the rim of the 20 vessel and said rigidifying element being fastened to the inner members of said telescopic arms.

In witness whereof I claim the foregoing as my invention, I hereunto append my signature this tenth day of April, 1920. 25

LAWRENCE MAPLES.
